AUTOMOBILE LICENSE PLATE

Frank J. Gantnier, Binghamton, N. Y., assignor of
one-half to Robert F. Gantnier, Binghamton,
N. Y.

Application November 3, 1944, Serial No. 561,724

6 Claims. (Cl. 40—125)

1

This invention relates to certain new and useful improvements and structural refinements in automobile license plates and tags, and the primary object of the invention is to provide a reliable and adequate assemblage of parts combining their functions in the provision of a standard or conventional plate and an annual city and year attachment therefor.

For many years it has been the customary practice of city, State and other authorities to issue new license tags and plates yearly. Thus, each plate was self-sufficient for full licensing and identification purposes. Lately, for reasons well known to the reader, it has become the practice to utilize clips and attachments and to use the main plate from year to year. Clips and attachments have been constructed to denote, primarily, the change of the year.

The purpose of the present invention is to provide an attachment such as can be used with the regulation tag or plate, said attachment serving the same purposes of makeshift clips and analogous auxiliary plates, the same embodying certain seemingly desirable, fool-proof and theft-proof characteristics, whereby to provide a more complete and finished assemblage possessed of greater ornamentation and utility.

More specifically, the renewable part of the attachment is adapted to be made from plastic, wood, or specially treated cardboard or other economical and readily available material, the same having a disruptable panel or tear strip for authorized removal when said part of the complete assemblage is to be replaced from year to year.

Other features and advantages will become more readily apparent from the following description and the accompanying illustrative drawings.

In the drawings, wherein like numerals are employed to designate like parts throughout the same:

Figure 1 is a front elevational view of a conventional metal or equivalent license plate or tag equipped with the annually renewable city and year attachment constructed in accordance with the principles of this invention.

Figure 2 is a top edge view of the structure seen in Figure 1 with the detachable or disruptable panel being partly torn off.

Figure 3 is a fragmentary elevational view showing the parts remaining after said panel is completely peeled off.

Figure 4 is a central longitudinal sectional view of the complete assemblage seen in Figures 1 and 2.

2

Figure 5 is an enlarged detailing view of a fragmentary type taken approximately on the plane of the line 5—5 of Figure 4, looking in the direction of the arrows.

5 Figure 6 is a longitudinal sectional view through the bodily removable attachment per se.

Figure 7 is a plan view of the insert or core strip seen in the attachment appearing in Figure 6.

10 Figure 8 is a detail view of a retaining clip forming a part of the complete structure.

Figure 9 is an enlarged cross section on the plane of the line 9—9 of Figure 4.

15 Referring now to the complete assemblage in a general way, the usual plate or tag-supporting bracket or fixture is indicated at 10 (see Figs. 2, 4 and 5). The regular or customary license plate 11 is bolted thereon by strong steel or equivalent bolts 12 whose threaded shanks are longer

20 than usual in order to accommodate the present invention. Threaded on each shank is a special conical nut 13 whose cylindrical body portion is provided with an endless groove forming a keyway which serves in a manner to be hereinafter de-

25 scribed. Suitable washers are interposed, as at 14, between the nut, bolt and plate 11. Thus, it will be seen that the plate 11 is bolted on the bracket 10 by special bolts, special nuts and associated washers. Once the plate is applied, these

30 parts 12, 13 and 14 remain constantly in place, it being the thought that the plate 11 is a lifetime proposition, lasting at least for the life of a car. It is also evident, in this connection, that the owner of the car has a constant license number

35 from year to year.

The auxiliary part or attachment is indicated at 15, and, as before mentioned, may be made of plastic, wood, some suitable composition, or even waterproof cardboard. This is of general rec-

40 tangular form and of a length less than the main tag. In fact, its end portions extend only slightly beyond the bolt and nut mounts. This part 15 is provided with a bore which extends completely therethrough, the same being open at opposite

45 ends and is made up of a main base or body portion 16, and a disruptable, removable or tear strip 17, the latter having an extension 18 forming a finger grip at one end, and also having longitudinally spaced rectangular projections 19. These

50 are seen in Figure 6 as socketed on their inner sides to provide the clearance space for the shank of the bolt, extended end portion of the nut, as seen in Figure 5. At the point of juncture between the extension 19 and the strip 10, there is

55 an undercut groove 20 which serves as a pocket to

accommodate one of the keying clips 21, as detailed in Figure 8. The clip is in the form of a split ring 22 of resilient or equivalent wire having its free ends 23 directed inwardly and fashioned to serve as keepers, these keepers being fitted into the keying grooves formed in the body portion of the aforementioned nuts 13.

An insertible and removable metal strip, this being a permanent and re-usable part, is indicated at 24, and this slips into one end of the bore in the attachment 15, as brought out in best advantage in Figure 6. It is provided in one end with a lateral finger grip 25 to facilitate handling and also provided at longitudinally spaced points with nut-receiving holes 26, these snugly surrounding the nut, or nuts, as brought out in Figure 5. It is to be mentioned at this time that the body portion 16 of the attachment is provided with holes 26a which align with the holes 26. The numerals 27 designate relatively thick rubber gaskets which are interposed and surround the bolt and nut assemblage as well as the washers, these serving as cushioning elements and preventing rattling of the parts.

The directions for installation and use are as follows: First, bolt the main license plate 11 to the bracket 10, this in the usual manner, using the two bolts 12, lock washers 14 and a special assembling and clamping nuts 13. Be sure to center the main plate 11 and align the bolts so that the holes 26 in the aforementioned metal strip 24 will slip over the nuts before tightening. Next, place the spring clips 21 in the pockets 20 of the attachment 15, after which slide the metal strip 24 into the bore or slot provided therefor, being careful to keep the spring clips between said metal strip and the projections 19 against which the spring clips rest. Then, place the rubber gaskets 27 in the holes 26a to rest against the bridging apertured portions of the metal strip 24. Next, place the holes 26 over the nuts 13 and press the parts into place, being sure to press hard enough to engage the spring clips with the keying grooves in the nuts 13. There may be a slight back pressure from the rubber gaskets, these being inserted for that purpose and also to prevent rattling.

To change the license plate from one year to another, all that is necessary is to catch hold of the finger piece 18 and to exert a ripping or tearing action thereon to disrupt and "peel out" the panel or tear strip 17. This can be done easily because this strip is either made thin for that purpose or scored along its longitudinal edges, as indicated at 28 (see Fig. 9). When this tear strip 17 is completely removed, it will expose the spring clips and they can then be removed. The main plate is left in place, which means that it is not necessary to loosen or move the bolts out of alignment. All parts but 15 are re-used. It might be added that if 24 is considered as a part of 15, it is not to be construed as such, for it being a permanent metal part, it can be used over, if desired. All that the car user needs to obtain is the part 15 minus the insertible and removable strip 24, if he already has one from the previous year. The installation of the next year attachment plate is accomplished by following the instructions already given for the initial installation.

This invention has many advantages. First, the license number is not changed each year, making it easier to remember. Second, it makes stealing the plate difficult, if not impossible, as the bolts are concealed in such a way that the

plate must be destroyed or damaged in removing it. Third, it will prevent people with two or more cars from shifting licenses from one car to another. Fourth, there are many new types of license plates that have many advantages, but are not used because they are too expensive. Only one main plate is necessary for the life of the vehicle, and the annual auxiliary plate or attachment can be made of an inexpensive material. Fifth, the latter can be made of plastic, fiber, waterproof cardboard, or any cheap material.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. In a structural assemblage of the class described, in combination, a relatively stationary supporting bracket, a license plate of a conventional type, bolts passing through apertures in the bracket and plate, said bolts having long shanks extending outwardly, and clamping and attachment accommodation nuts on the shanks of said bolts, said nuts being provided with marginal endless grooves serving as keyways to accommodate special attachment-retaining keys, and an attachment adapted to be mounted on the license plate within the marginal borders thereof, said attachment being provided with expandible and contractible retaining keys having portions to fit into the keyways in said nuts.

2. In a structural assemblage of the class described, in combination, a bracket, a plate, bolts extending through the bracket and plate, nuts on said bolts, said nuts having retention grooves formed therein, an attachment bearing the city and year insignia, said attachment being adapted to be replaced from year to year and being provided at opposite ends with bolt and nut accommodation holes, said holes being adapted to accommodate spring clips, spring clips mounted in said holes and having portions adapted to be snapped into the grooves in said nuts.

3. In a structural assemblage of the class described, in combination, a bracket, a plate, bolts extending through the bracket and plate, nuts on said bolts, said nuts having retention grooves formed therein, an attachment bearing the city and year insignia, said attachment being adapted to be replaced from year to year and being provided at opposite ends with bolt and nut accommodation holes, said holes being adapted to accommodate spring clips, spring clips mounted in said holes and having portions adapted to be snapped into the grooves in said nuts, said attachment also including a removable metal strip having holes to snugly embrace the nuts, said metal strip being held in place by said spring clips.

4. An attachment for a conventional license plate adapted to contain and display changeable city and year insignia for use in association with license numbers carried by the plate comprising a body constructed from light weight readily disposable and inexpensive stock, said body being provided at opposite ends with bolt and nut accommodation holes, a readily removable tear strip on the face thereof having outstanding pro-

jections socketed, with the sockets in alignment with said bolt and nut holes, said body also having a longitudinal centrally arranged bore extending longitudinally therethrough, and a removable metal strip insertable into said bore, said strip being provided adjacent opposite ends with nut embracing holes in alignment with the bolt and nut holes in said body.

5. A permanent fool-proof and theft-proof identification plate with an auxiliary indication attachment for an automobile or the like comprising, in combination, a standard license plate capable of being permanently fastened to a conventional plate supporting bracket, bolts with associated washers and conical nuts, said nuts each having a cylindrical body portion provided with an endless groove serving as a keyway to accommodate special attachment retaining keys, an auxiliary attachment indicating the changeable data on the said permanent plate-like annual and location changes, said auxiliary attachment comprising a main base portion and a disruptable tear strip, the latter provided with an extension forming a finger-grip and with longitudinally spaced hollow projections corresponding in number with the number of said bolts, said auxiliary attachment being provided with bolt holes extending therethrough, said hollow projections providing clearance pockets for the shanks of said bolts and for the extended portions of the said nuts, keying clips, each clip being in the form of a split ring having its free ends directed in-

wardly and fashioned to serve as keepers adapted to snap into the keying grooves in said nuts, said main base portion having at one end a lateral finger-grip and being provided at longitudinally spaced points with bolt and nut-receiving holes snugly surrounding said nuts, the body portion of the said auxiliary attachment being provided with bolt and nut holes in alignment with the said bolt and nut-receiving holes, all the said elements in associated mechanical combination keeping the bolts concealed in such a way that the license plate cannot be removed without considerable damage to it, rendering it unusable.

6. An attachment for a conventional license plate adapted to contain and display changeable city and year insignia for use and association with license numbers carried by the plates comprising a body constructed from lightweight readily disposable and inexpensive stock, said body being provided at its opposite ends with bolt and nut accommodation holes; a readily removable tear strip on the face thereof having outstanding projections provided with sockets in alignment with said bolt and nut holes, said body also having a longitudinal centrally arranged bore extending longitudinally therethrough, this to accommodate a removable metal strip provided at opposite ends with nut embracing holes in alignment with the bolt and nut holes in the body.
